DOUBLE SINK

William C. Groeniger, Columbus, Ohio, assignor
to John B. Pierce Foundation, New York, N. Y.,
a corporation of New York

Application December 29, 1934, Serial No. 759,610

3 Claims. (Cl. 4—187)

My present invention relates to plumbing fixtures, and more particularly to an improved double sink.

A feature of my invention is the combination 5 into a unitary structure of a plurality of sinks.

Another feature of my invention is the combination into a unitary structure of a plurality of sinks utilizing a common waste outlet.

A further feature of my invention is the combination 10 into a unitary structure of a plurality of sinks, and in which structure the dividing wall between the two sinks constitutes a housing chamber for the waste valves, such chamber communicating with a common waste outlet.

15 A still further feature of my invention is the utilization of the upper end of the common division wall between the two sinks as a bearing member for the waste line valve operating elements.

20 Other features and novel forms of construction of my device will appear as the description of the invention progresses.

In the accompanying drawings,

25 Fig. 1 is a plan view of my improved double sink;

Fig. 2 is a section on the line 2—2 of Fig. 1, showing one of the waste valves in closed position;

30 Fig. 3 is a view, similar to Fig. 1, and showing the waste valve in open position;

Fig. 4 is a section on the line 4—4 of Fig. 1;

Fig. 5 is a partial sectional elevation of the upper end of the dividing wall between the sinks; and

35 Fig. 6 is a section on the line 6—6 of Fig. 4.

Referring to the drawings, 10 and 11 designate sinks, arranged side by side, and formed integral with each other, and with a splash board 12 arranged along the back edges thereof. Also 40 formed integral with the sink 10 and with the splash board 12 is a drain board 13.

The dividing wall between the sink 10 and the sink 11 is formed of the wall 14 of the sink 10 and the wall 15 of the sink 11, such walls being 45 spaced apart from each other, and joined integral with a top member 16 at the top ends of the walls 14 and 15. These three elements 14, 15 and 16 define a chamber 17 in which is housed the waste line valves and operating means therefor, and 50 which will be hereinafter described in detail. As the complete area of the walls 14 and 15 is not utilized in the building of the chamber 17, wall members, as the wall members 18, are used to limit the extent of the chamber 17, and to maintain such chamber fluid tight. The lower end of

the chamber 17 has a closure bottom 19 formed integral with the walls 14 and 15 and with the wall members 18, such closure bottom 19 being provided with an orifice 20, and to and through which may be attached one end of a waste line. 5

The chamber 17 is divided into two parts by a baffle plate 21 extending between and formed integral with the walls 14 and 15, and which extends downward beyond the lower limits of the walls 14 and 15, terminating at any convenient 10 point above the lower wall of the closure bottom 19, see Fig. 4. This dividing wall or baffle plate 21 prevents back flow from the chamber 17 from the sink 10 into the sink 11 or vice versa.

In the walls 14 and 15 are formed orifices 22 15 and 23 respectively, which permit flow of waste liquids from the sink 10 and sink 11 into the chamber 17. Both the orifices 22 and 23 are similar in construction, arrangement and purpose, and therefore a description of one of them will 20 suffice in the present case.

Referring to Figs. 2 and 3, a rectangular ring 24 has formed on its outer peripheral edge an angle groove in which is mounted a washer or gasket 25, and a central web 26 of the ring 24 25 is drilled and threaded to receive a flat head screw 27 passing through a centrally arranged perforation in a screen plate 28, which plate is located on the opposite face of the wall 15 from the ring 24. The screw 27 holds the ring 24 and screen 30 plate 28 in position over and in the orifice 23.

Formed integral with and on one face of the thus spidered ring 24 are wedge shaped guides 29 and 30, adapted to cooperate with a wedge shaped gate valve 31. The wedge shaped gate valve 31 35 has a face which engages the inner edge of the ring 24, which acts as a valve seat.

Further referring to Figs. 2 and 3, it is obvious that if the wedge shaped gate valve 31 is moved downwardly from the position shown in Fig. 3, 40 that such valve 31 will be moved into engagement with the referred to valve seat on the inner face of the ring 24, and when the valve 31 reaches its lowermost position, as shown in Fig. 2, the valve 31 and seat will be in close association. 45 Such valve 31 is of the shear type, is easy to operate, and is self cleaning. The particular form and function of the improved valve 31 forms no part of my present invention, being specifically described and claimed in my co-pending application Serial No. 29,904, filed July 5th, 1935. 50

Formed on the rear face of the valve 31 is a shaft 32 to which is pivotally attached the lower end of a rod 33. A pin 46 passing through a perforation in the shaft 32 (see Fig. 6) prevents 55

accidental removal of the rod 33 from the shaft 32. The upper end of this rod 33 is threaded as indicated at 34, and this threaded end screws into the lower end of an operating handle 35.

5 The top member 16 joining the walls 14 and 15 does not extend over that portion of the chamber 17 immediately above the orifices 23, such top member 16 being finished off by the projections 36. Between these projections 36 and resting 10 on the upper edge of the walls 14 and 15 is a combined closure and drain 37. Each combined closure and drain 37 is provided with a plurality of transversely arranged slots 38 and with a perforation 39 and in which perforation the operating handle 35 is a sliding fit. The upper end 15 of the operating handle 35 is shown provided with a knob 40, having a diameter greater than that of the perforation 39, thereby to preclude accidental dropping of the operating handle 35 through the perforation 39. Formed integral 20 with the rod 33 and below the lower limits of the operating handle 35 is formed a member 41, this member 41 being of a diameter greater than the diameter of the perforation 39 in the closure member 37, to thereby prevent too great a range of upward movement of the rod 33 and therefore preventing the valve member 31 from being moved out of its position relative to the wedge shaped guides 29.

25 30 The structure above described provides a solution for the difficult problem of assembling two or more sinks and/or basins into a unitary structure and with the minimum required amount of piping. Also, the structure above described permits the use of pre-fabricated or factory fabricated waste line units, and in addition all parts of the apparatus are readily accessible for cleaning. Further the utilization of the single combined waste chamber reduces materially the 35 number of possible leakage points in an apparatus of this type.

40 Various modifications of my invention will readily suggest themselves to those skilled in this art, and I do not therefore limit myself to the exact structure shown and described, except as 45 pointed out in the appended claims.

I claim:

1. An improved plumbing fixture, comprising 50 sinks arranged side by side, said sinks being provided with discharge openings disposed at juxtaposed sides of said sinks, said juxtaposed sides of said sinks being spaced by a clearance from one another, an outlet chamber communicating with the interior of said clearance and with said discharge openings of said sinks, said outlet chamber extending below the bottoms of said sinks and provided thereat with opening means arranged for connection and communication with

suitable outlet means, a baffle plate extending imperforately from opposite walls of said outlet chamber above the discharge openings of said sinks, said baffle plate further extending below said discharge openings of said sinks and terminating at a location above said opening means of said outlet chamber, whereby upon discharge of said sinks, singly or plurally, backflow from one sink to the other is precluded.

2. An improved plumbing fixture, comprising 10 sinks arranged side by side, said sinks being provided with discharge openings disposed at juxtaposed sides of said sinks, said discharge openings being arranged out of alignment with one another, said juxtaposed sides of said sinks being 15 spaced by a clearance from one another, an outlet chamber communicating with the interior of said clearance and with said discharge openings of said sinks, said outlet chamber extending below the bottoms of said sinks and provided thereat with opening means arranged for connection and communication with suitable outlet means, a baffle plate extending imperforately from opposite walls of said outlet chamber above the discharge openings of said sinks, said baffle plate 20 further extending below said discharge openings of said sinks and terminating at a location above said opening means of said outlet chamber, whereby upon discharge of said sinks, singly or 25 plurally, backflow from one sink to the other is precluded.

3. In a plumbing fixture, a unitary structure including two sinks, said sinks being respectively provided with lowerly disposed discharge openings, said sinks being laterally spaced from one another to provide a clearance, an outlet chamber communicating with such clearance and disposed between said sinks, said discharge openings communicating with the interior of said outlet chamber, said outlet chamber extending below the bottoms of said sinks and provided thereat with opening means arranged for connection and communication with suitable outlet means, said outlet chamber when connected with such outlet means being at its portions below the bottoms of said sinks wholly closed, a wall portion extending imperforately from an upper portion at one of said juxtaposed sides of one sink to an upper portion of the juxtaposed side of the other sink, to thereby form thereat a top wall of the upper portion of the interior of said clearance, the remainder of the upper termination of said clearance being partially closed by depressed wall means, provided with drain openings communicating through said clearance with said outlet chamber for receiving soap or the like.

WILLIAM C. GROENIGER.
